UNITED STATES PATENT OFFICE.

FREDERICK PERCY DRIVER, OF LONDON, ENGLAND, ASSIGNOR TO OSRAM-ROBERTSON
LAMP WORKS, LIMITED, OF BROOK GREEN, HAMMERSMITH, LONDON, ENGLAND.

MEANS FOR SUPPORTING ELECTRODES IN IONIC TUBES.

1,335,159.

Specification of Letters Patent. Patented Mar. 30, 1920.

Application filed May 22, 1918. Serial No. 235,951.

To all whom it may concern:

Be it known that I, FREDERICK PERCY DRIVER, a subject of the King of Great Britain, residing at London, England, have 5 invented new and useful Means for Supporting Electrodes in Ionic Tubes, of which the following is a specification.

This invention relates to means for supporting electrodes in ionic tubes, more particularly when such tubes are used as transmitting or receiving valves in wireless telegraphy. The invention is especially useful for ionic tubes adapted to dissipate impulses of high power, wherein a cathode 15 constituted by a filament of metal is surrounded by a substantially cylindrical anode formed of sheet metal, with a grid interposed between the anode and cathode so as to surround the latter, the grid being made 20 of thin wire usually in the form either of a spiral coil, or of a series of straight wires extending substantially parallel to the cathode filament, or of a substantially cylindrical cage of wire gauze.

In constructions hitherto in use, great difficulties have been encountered in insuring that the several supporting members were rigidly held and that the intervening insulation spaces were maintained uniformly of sufficient width to withstand the very high voltages necessary, during the exhaustion of the bulb, in order that the utmost practicable vacuum might be attained. The method heretofore employed has been 30 to seal or melt the supporting members into the glass, with the result that the attachment was very fragile and the glass liable to fracture more especially under the stresses set up by the expansion of the metal supporting-members when heated.

The present invention is directed to providing improved means of supporting the members or some of them, whereby the risks due to variations of temperature will 45 be as far as possible eliminated; the improved construction being more especially applicable either to the support of the anode and grid from opposite ends of the bulbs respectively, or to the support of the anode alone from both ends of the bulb, which latter arrangement the present invention is adapted to permit.

According to the invention, the outer ends of a set of longitudinally-extending

carrier-bars (usually three in number) for 55 the anode or grid as the case may be, are attached preferably by riveting, to one or more metal clips adapted to firmly embrace a reentrant glass tube which is sealed by its open outer end into the outer end of the 60 corresponding neck of the bulb and closed at its inner end so as to constitute a hermetic closure for the bulb. Each clip comprises a band of thin sheet metal bent to 65 conform to the cylindrical periphery of the glass tube, security of grip being preferably obtained by providing one end of the band with a tongue adapted to be passed through a transverse slot in the opposite end of the band and folded back upon itself so as to 70 prevent subsequent loosening of the clip by retraction of the tongue through the slot.

In the accompanying drawings, Figure 1, which is a side elevation of one neck of an 75 ionic tube with the adjacent portion of the bulb, shows a cylindrical anode supported from one end according to the present invention, the other members required to complete the structure of the tube as a whole being omitted. Fig. 2, which is a side elevation of one neck of an ionic tube (which 80 may be the same tube as that illustrated in Fig. 1) with the adjacent portion of the bulb, shows a grid supported from one end according to the invention, the grid being 85 formed by a spiral coil of thin wire wound about a group of straight parallel wires, while the other members required to complete the structure of the tube as a whole are omitted. Fig. 3 is a side elevation of an 90 ionic tube showing a cylindrical anode supported from both ends according to the invention, the other members required to complete the structure of the tube as a whole being omitted. Fig. 4 is a section on line 95 4-4 of Fig. 1, drawn to a larger scale. Fig. 5 is a section on line 5-5 of Fig. 4. Fig. 6 is a perspective view of one of the metal clips already referred to, shown separately.

Referring first to Figs. 1, 4, 5, and 6, it will be seen that to the cylindrical anode 11 are riveted the inner ends of a set of three longitudinally-extending carrier-bars 12, 13, 14 whereof the outer ends are riveted to a 105 pair of metal clips 15, 16 placed side-by-side so as to be adapted to embrace a glass tube 17 which is closed at its inner end and sealed

by its open outer end, at 18, into the outer end of the corresponding neck 19 of the bulb 20; the tube 17, which is reentrant with reference to the neck 19 and disposed coaxially therewith, thus constituting a hermetic closure for that end of the bulb.

Each clip 15 or 16 consists of a band of thin sheet metal bent to conform to the cylindrical periphery of the reentrant glass tube 17, and is securely clasped about the latter by a tongue 21 at one end of the band being passed through a transverse slot 22 in the opposite end (see Fig. 6) and folded back upon itself as indicated in Fig. 4. The slotted end of the band is preferably formed, as shown, with a tubular roll-edge 23 so as to obviate risk of the tongue 21 being broken when doubled upon itself tightly: the tubular roll 23 of one of the clips (16 in the example illustrated) conveniently serving, moreover, for the reception of a wire 24 which is soldered into the roll and coupled to the external electrical connection with the anode 11. For this purpose the wire 24 is shown as joined at 25 to a wire 26 which is led out of the bulb by being passed through and sealed at 27 into the side wall of the reentrant glass tube 17, through the bore of which tube the wire 26 extends to the outside as indicated.

A single clip might suffice for attaching the carrier-bars 12, 13, 14 to the reentrant glass tube 17; but in order to insure steadiness it is preferred to employ two clips side-by-side as shown, so as to afford a longer bearing for the support of the overhanging weight of the anode; the clips being spaced apart so as to be adapted, by gripping the tube 17 at opposite sides of a slight outward projection 28 formed thereon, to prevent displacement of both clips in either direction lengthwise of the tube. For the sake of rigidity, the carrier-bars 12, 13, 14 (which are spaced apart at equal angular distances around the axis of the anode 11) may be formed, throughout the greater part of their length, of substantially L-shape in cross-section, as indicated in Fig. 5.

Referring now to Fig. 2, it will be seen that the grid consists of a spiral coil 29 of thin wire wound about a group of three straight parallel wires 30, 31, 32 attached respectively to, and in alignment with, three carrier-bars 33, 34, 35 which are riveted to a pair of metal clips 15, 16, similar in all respects to those already described with reference to Fig. 1. These clips are clasped side-by-side about a reentrant glass tube 17 which is closed at its inner end and sealed by its open outer end, at 18, into the outer end of the corresponding neck 19 of the bulb so as to constitute a hermetic closure for that end of the bulb 20; the clips 15, 16 being spaced apart and separated, as before, by an outward projec-

tion 28 on the tube 17 so as to be held against displacement in either direction lengthwise of said tube. In this case a wire 36, soldered into the roll-edge on the end of the clip 16, is joined at 37 to a wire 38 which is led out of the bulb by being passed through and sealed at 39 into the closed inner end of the tube 17, through the bore of which the wire 38 extends to the outside as indicated.

The improved supporting means are well adapted for use at both ends of the anode, which may thus be held with the maximum practicable security in position within the bulb. Such an arrangement is illustrated in Fig. 3, wherein the supporting means at each end of the cylindrical anode 11 are shown as substantially identical with those described with reference to Fig. 1 for one end of the anode, the same reference numerals denoting corresponding parts in both figures, and at both ends of the bulb. In this case the electrical connection with the anode is shown as established by means of a wire 40, which is soldered into the roll-edge 23 on the end of one of the clips 16 and led directly to the exterior of the bulb 20 through the wall of the latter, into which the wire is sealed at 41.

Having now particularly described and ascertained the nature of my said invention and in what manner the same is to be performed, I declare that what I claim is:

1. The combination of a glass bulb having a reentrant glass tube constituting a hermetic closure for said bulb, a metal clip embracing said reentrant tube and having a slot, a tongue on said clip extending through said slot and folded back upon itself whereby said clip is detachably secured upon said reentrant tube, an electrode and a plurality of longitudinally extending carrier-bars attached at their outer ends to said clip and at their inner ends to said electrode.

2. The combination of a glass bulb having a reentrant glass tube constituting a hermetic closure for said bulb, a metal clip embracing said reentrant tube and having a slot, a tubular roll at one end of said clip adjacent to said slot, a tongue at the other end of said clip extending through said slot and about said roll and folded back upon itself whereby said clip is detachably secured upon said reentrant tube, an electrode, and a plurality of longitudinally extending carrier-bars attached at their outer ends to said clip and at their inner end to said electrode.

3. The combination of a bulb having a reentrant glass tube constituting a hermetic closure for said bulb, a projection extending outwardly from said reentrant tube, a pair of metal clips embracing said tube upon opposite sides of said projection, an elec-

trode and a plurality of carrier-bars having their inner ends attached to said electrode and their outer ends attached to said clips.

4. The combination of an ionic tube having reëntrant tubes at its opposite ends, metal clips embracing and detachably secured upon said reëntrant tubes, a cylin-

drical anode in said ionic tube and a plurality of carrier-bars extending in opposite directions from the ends of said anode and 10 having their inner ends attached thereto and their outer ends attached to said clips.

FREDERICK PERCY DRIVER.
